(57) **CLAIM**

The ornamental design for a multi-functional router base, as shown and described.

DESCRIPTION

FIG. 1 is a front, top, left side isometric perspective view of a multi-functional router base in accordance with my design. FIG. 2 is a rear, bottom, right side isometric perspective view of a multi-functional router base as shown in FIG. 1. FIG. 3 is a front elevation view of multi-functional router base as shown in FIG. 1.

FIG. 4 is a rear elevation view of multi-functional router base as shown in FIG. 1.

FIG. 5 is a top plan of multi-functional router base as shown in FIG. 1.

FIG. 6 is a bottom plan of multi-functional router base as shown in FIG. 1.

FIG. 7 is a left side elevation view of multi-functional router base as shown in FIG. 1.

FIG. 8 is a right side elevation view of multi-functional router base as shown in FIG. 1; and,

FIG. 9 is a cross-sectional view of the multi-functional router base shown in the direction of line 9-9 of FIG. 8. The broken lines depict portions of the multi-functional router base that form no part of the claimed design.

1 Claim, 7 Drawing Sheets
